[57] ABSTRACT

Mixture agents consisting of mixed coloring agents and oxidizing agents are enclosed in a light pervious envelope of glass or similar material of an electric flash bulb. The coloring agents thereof are adhered to the inside wall of the flash bulb by ignition of combustible material within the bulb, whereby the envelope of the flash bulb is colored and may be used as an indicator in the maintenance of certain equipment.

FIG. 1

FIG. 2

FIG. 3

FIG. 4

FIG. 5

FIG. 6

ELECTRIC FLASH BULB FOR USE AS INDICATOR

BACKGROUND OF THE INVENTION

1. Field of the Invention

This invention relates to an electric flash bulb for use as an indicator having an envelope which becomes colorfully colored upon ignition.

2. Description of the Prior Art

As is well known, among the problems encountered in the maintenance of electric power transmission lines are those involving the ordinary lightning bolts often associated with thunderstorms. If such lightning bolts strike at a transmission line, the current of the lightning discharges to the ground through the tower and shorts the insulator, or even if the lightning only strikes in the neighborhood of the transmission line, its current discharges to induce high voltage to the ground through the tower and shorts the insulator. The insulator is often destroyed by such discharge of lightning bolts, so that it is necessary for the maintenance workers to make periodical rounds of inspection thereof. Such inspections were very inconvenient, as climbing to the tower inherently involves a degree of risk to the worker. Such an inconvenience can be dissolved by providing a photoelectric flash lamp in the discharge circuit of the tower, so that when an electric discharge occurs because of a flow of the energy of a bolt of lightning into the tower, the flash lamp is ignited, and the inner bulb wall of the flash lamp becomes discolored thereby. Therefore, the maintenance workers could inspect the faults of transmission lines by locating the discolored flash bulb in the discharge circuit of the respective tower.

But, in the case of presently available conventional photoelectric flash lamps employed as indicators, there are many defects, such as, for example, the inner wall of the bulb not being adequately discolored for ready observation from a distance, and even if coloring agents are used, the ignition thereof becomes too weak.

SUMMARY OF THE INVENTION

Accordingly, it is an object of the present invention to provide an improved electric flash bulb for use as an indicator having a light pervious envelope being sealed to enclose a mixture of agents comprising coloring agents and oxidizing agents, for adhering on the inner wall of the envelope, such coloring agents being adapted to be scattered by the explosion caused by ignition of combustible material provided in the envelope.

Another object of the present invention is to provide an improved flash bulb for use in the maintenance of electric power transmission lines, traffic signal systems, for inspection of leakage of electricity, or in measurement equipment.

Another object of the present invention is to provide an improved electric flash bulb for use as an indicator having a light pervious envelope sealed to enclose a mixture of agents containing combustible agents for activating a scattering process of coloring agents.

The foregoing and other objects are attained according to at least one aspect of the present invention through the provision of an electric flash bulb having a light pervious envelope and being sealed to enclose a mixture of coloring agents and oxidizing agents. Upon

ignition, the coloring agents are coated on the inner surface of the bulb to radically change the color to permit easy discrimination of the change. Additionally, an uneven acrylic synthetic resin film is coated on the

inner surface of the bulb for improving the adhering characteristics of the coloring agents thereto, and another coating of acrylic synthetic resin is applied to the outer surface of the bulb for protecting the same and making it more durable.

BRIEF DESCRIPTION OF THE DRAWINGS

Various other objects, features and attendant advantages of the present invention will be more fully appreciated as the same becomes better understood from the following detailed description, when considered in connection with the accompanying drawings, wherein like reference numerals designate like or corresponding parts throughout the several FIGURES, and in which:

FIG. 1 is a front, partially cross-sectional, view of an electric flash bulb constructed in accordance with the present invention;

FIGS. 2 to 4 are front views of several different embodiments of this invention; and,

FIGS. 5 and 6 are enlarged partial cross-sectional views of the bulb wall of other embodiments of this invention.

DETAILED DESCRIPTION OF THE PREFERRED EMBODIMENTS

Referring now to the drawings, and more particularly to FIG. 1, an electric flash bulb is shown having a glass bulb 1 as a sealed light pervious envelope coated with a synthetic resin film 2 on the outer surface thereof as a protector, and on the top portion of the inside wall of the envelope, there is adhered a lump 3 composed of a mixture of agents.

The mixture of agents or lump 3, consists of a coloring agent, such as a chemical dyestuff, for example, rhodamine, para red (para nitro aniline red), indigo pure (trademark of B.A.S.F.), auramine or methylene blue, and an oxidizing agent, for example, potassium chlorate ($KClO_3$), potassium perchlorate ($KClO_4$), lead dioxide (PbO_2) or manganese dioxide (MnO_2), coupled with a binder, for example, nitrocellulose, or the like. These coloring agents are combustible materials, while the oxidizing agents have the ability of assisting in the combustion of combustible materials, such as dyestuff. The mixture ratios of the coloring agents, the oxidizing agents and the binder are shown in the following table, indicated as Table 1.

TABLE 1

Color of agents	coloring agents	Oxidizing Agents	Binder
red	rhodamine 25% para red 35%	potassium chlorate 25%	15%
blue	methylene blue 20% indigo pure 40%	potassium chlorate 30%	10%
green	methylene blue 20% indigo pure 30% auramine 10%	potassium chlorate 30%	10%

While they are not necessarily mixed precisely according to the rates indicated, the rates appearing in

Table 1 are those which have been found to be most suitable for achieving the objects of this invention.

Enclosed within the bulb are small wires or small pieces or films of aluminum (Al) or zirconium (Zr) as a charge of combustible materials 4, and a pair of lead wires 6 having a filament 7 connected to the tops thereof and coated primers 8 at the points of connection of the filament 7 and the lead wires 6. Oxygen is also enclosed within the bulb as a combustion-promoting gas, and other inactive gases, such as, for example, nitrogen gas (N) or argon gas (A), are also enclosed as combustion-suppressive gases having such properties for suppressing to a suitable low temperature the temperature of the inner space of the bulb. For example, the quantity of combustion-suppressive gas may be up to 15 percent of the volume as compared with that of oxygen. The envelope is mounted on a base 9 being provided with electrodes 10 and 11 for supplying electric current to the bulb.

In the operation of the embodiment shown in FIG. 1, the flash bulb is ignited by the primers 8 adhered to the connecting points of the filament 7 when a current flows to the filament 7. The charge of combustible material 4 is burned by the primers 8 with oxygen, whereupon light energy and thermal energy are produced. In this case, such action of the flash bulb is accomplished by using thermal energy, but a part of the coloring agents is burned, and almost all of it is evaporated.

FIG. 2 illustrates another embodiment of this invention being shaped as a conventional incandescent lamp type bulb and being similar to the embodiment illustrated in FIG. 1, which has a particularly long portion 12 extended from at least one of the lead wires 6, and in which the mixture of agents 3 are adhered to this long portion 12.

FIG. 3 illustrates another embodiment of this invention in which the flash bulb 1 has enclosed therein many pieces of colored paper 13. The mixture of agents 3 are in this case adhered to both of the lead wires 6 on the middle portions thereof as the ignitor 5. Thus, when the filament 7 is ignited by an electric current, the primers 8 burn, and then the colored papers 13 burn with the combustion-promoting gas, and are caused to disappear, whereby, for example, if the color of the colored paper is red, and the color of the coloring agent obtained by ignition is blue, the flash bulb is discolored from red to blue. Therefore, an inspector can clearly discriminate the bulb in which such discoloration has occurred.

Yet another embodiment of flash bulb is illustrated in FIG. 4, being of the baseless type incandescent lamp, which particularly comprises a filament 7 having the mixture of agents 3 directly adhered thereon as the ignitor 5. If this filament is ignited by an electric current, the mixture of agents burns without a combustion-promoting gas.

Still another embodiment of a flash bulb is illustrated in a partially enlarged cross-sectional view in FIG. 5, wherein the bulb wall is improved by coating the inside surface thereof with an acrylic resin film 14 for providing an uneven surface on the inner surface of the bulb. A bulb wall having an uneven surface can provide improved adhesive characteristics. Thus, to provide improved coloring, upon evaporation of the coloring agents, the agents must be well adhered to the inner surface of the envelope, and since the film 14 becomes soft from the heat attending the combustion of the

flashing, the coloring agents therefore are well adhered thereto. The synthetic resin film also serves to prevent explosion of the bulb.

If the ratio of enclosed quantity of inactive gas to the quantity of oxygen as a combustion promotive gas is less than 15 percent by volume, the temperature in the bulb will rise too high, and the coloring agents will be carbonized by the combustion thereof. Also, it is possible that the synthetic resin film 14 would be fully melted by the combustion.

A conventional flash bulb for taking photographs has previously been coated on its outer surface with a vinyl chloride synthetic resin film 15, as illustrated in FIG. 6, which cannot be used outdoors because of discolorizing and stiffening after one or two years from exposure to ultra-violet radiation and weather. If the bulb is covered with a glass cover, however, it becomes too large and too expensive. In order to avoid these defects, the outer surface of the bulb may be coated with an acrylic synthetic resin film having a thickness of more than 5 microns, or an acrylic resin film may be coated directly over the vinyl chloride synthetic resin film coated on the outer surface of the conventional flash bulb. Then, the bulb is made weatherproof.

The test results of the conventional bulb and of the bulb coated with an acrylic resin film appear in the following Table 2. The testing conditions were:

Testing equipment compulsory weatherproof testing equipment used in the weathering meter of the sun-shine type;

Thickness of the acrylic resin film on the outer surface of the bulb — 100 microns;
Humidity — 80 percent;
Temperature — $63 \pm 5^\circ\text{C}$;
Ultra-violet radiation — up to 8 mm W per cm.;
Rain fall — 18 minutes per 2 hours cycle.

TABLE 2

	Testing hours	Results
conventional bulb	100	surface is not changed
	300	one partially brownized
This embodiment	1,000	black and brownized
	100	surface is not changed
This embodiment	300	surface is not changed
	1,000	some brownized at the surface radiated by lamp

Therefore, the weatherproof performance is up to 3 times better than the conventional flash bulb.

Obviously, many variations and modifications are possible in light of these teachings. It is to be understood therefore that within the scope of the appended claims, the present invention may be practiced otherwise than as specifically described herein.

What is claimed as new and intended to be covered by letters patent is:

1. An electric flash bulb for use as an indicator comprising:
an envelope of light previous material;
coloring means including a mixture of agents comprising coloring agents and oxidizing agents sealingly enclosed within said envelope;
dispersing means within said envelope for dispersing said coloring means throughout said envelope through the release of thermal energy and for thereby coloring the interior of said envelope;

electrical ignition means disposed in said envelope for igniting said dispersing means and for initiating the dispersion of said coloring means throughout said envelope; and,

an acrylic synthetic resin film coated on the inner surface of said envelope for providing a rough surface to which said coloring agents readily adhere.

2. An electric flash bulb for use as an indicator, as defined in claim 1, wherein said ignition means comprises a filament, and said mixture of agents is directly adhered on said filaments.

3. An electric flash bulb for use as an indicator, as defined in claim 1, further comprising:

an acrylic synthetic resin film coated on the outer surface of said envelope.

4. An electric flash bulb for use as an indicator, as defined in claim 3, wherein said coating of acrylic synthetic resin on the outer surface of said envelope has a thickness of at least 5 microns.

5. An electric flash bulb for use as an indicator, as defined in claim 1, wherein said ignition means comprises a filament and at least a pair of leads connected thereto and said mixture of agents is directly adhered to said

leads.

6. An electric flash bulb for use as an indicator, as defined in claim 1, wherein said ignition means comprises a filament and at least a pair of leads connected thereto, and said mixture of agents is directly adhered to an extension of one of said leads.

7. An electric flash bulb for use as an indicator, as defined in claim 1, wherein said mixture of agents is directly adhered to the inner wall surface of said envelope.

8. An electric flash bulb for use as an indicator comprising:

an envelope of light pervious material; a mixture of agents comprising coloring agents and oxidizing agents sealingly enclosed within said envelope;

ignition means disposed in said envelope, whereby said coloring agents are coated on the inner wall surface of said envelope by said ignition means upon combustion; and

colored paper enclosed in said envelope, the color of said colored paper being different from that obtained by said coloring agents.
